UNITED STATES PATENT OFFICE.

ANTHONY DIXON BROGAN AND ANDREW MURRAY MALLOCH, OF GLASGOW,
SCOTLAND.

DESIGN FOR SURFACE ORNAMENTATION OF GLASS.

SPECIFICATION forming part of Design No. 28,846, dated June 14, 1898.

Application filed May 13, 1898. Serial No. 680,642. Term of patent 14 years.

To all whom it may concern:

Be it known that we, ANTHONY DIXON BROGAN and ANDREW MURRAY MALLOCH, citizens of the United Kingdom of Great Britain and Ireland, residing at Firhill, Glasgow, in the county of Lanark, Scotland, have invented and produced a new and original Design for the Surface Ornamentation of Glass, of which the following is a specification, reference being had to the accompanying drawing, forming part thereof.

The design is applied to the surface of glass and is represented in the accompanying drawing, which shows a plan view.

15 The leading or characteristic feature resides in the unitary design as shown; and it consists of a series of approximately square or rectangular figures disposed diagonally one in relation to another and whose corners 20 overlap so as to form smaller squares or rectangular figures at each of the four corners. Each of the squares is formed by two parallel V-shaped or prismatic ridges *a* and *b*, one within the space inclosed by the other. The 25 space intervening between the ridges *a* and *b* is filled up by V-shaped or prismatic ridges *c*, running at right angles to the ridges *a* *b*, and the small squares formed by the overlapping of the corners of the larger square figures 30 each inclose a rayonnant figure, formed by a series of prismatic or pyramidal ridges *d*, converging in a point in the center of said small square. Each of the sides of the larger square figures is indented at its mid-length, so that 35 the space inclosed by the sides of four adjoin-

ing squares assume the form of a sixteen-sided figure, bounded by the ridges *a* *b*, and centrally and symmetrically within said sixteen-sided figure is a figure formed by two V-shaped or prismatic ridges *e* and *f* of square 40 outline overlapping and disposed so that their sides intersect and form a series of triangles. Within said figure is a rayonnant figure of approximately circular contour formed by ridges *g*, converging to a central point. 45

Within each of the larger square figures is an ornate scroll formed by V-shaped or prismatic ridges *h* of curved outline branching symmetrically from a central point. The intervening spaces unoccupied by the several 50 figures referred to are filled up by small pyramids *i*, as shown; but as these merely form a background for the design they may be replaced by prismatic ridges or altogether omitted. 55

Throughout the drawing the black shading represents one side or face of each prismatic ridge and the white portion the other side or face.

We claim—

The design for the surface ornamentation of glass substantially as herein shown and described.

In witness whereof we have hereunto set our hands in presence of two witnesses.

ANTHONY DIXON BROGAN.
ANDREW MURRAY MALLOCH.
